PORTABLE BAR

William C. Stivers, Hayward, and Henry C. Stivers,
Castro Valley, Calif.

Application November 8, 1954, Serial No. 32,999

Term of patent 3½ years

(Cl. D33—14)

To all whom it may concern:

Be it known that we, William C. Stivers, a citizen of the United States and a resident of Hayward, Alameda County, California, and Henry C. Stivers, a citizen of the United States and a resident of Castro Valley, Alameda County, California, have invented a new, original, and ornamental Design for a Portable Bar, of which the following is a specification, reference being had to the accompanying drawing, forming a part thereof.

We claim:
